UNITED STATES PATENT OFFICE.

JAMES G. CALHOUN, OF EDINBURG, AND CALVIN B. GARRISON, OF CHARLES-TOWN, ASSIGNORS OF ONE-THIRD TO SAMUEL CALHOUN, OF EDINBURG, OHIO.

WIRE-TWISTING TOOL.

SPECIFICATION forming part of Letters Patent No. 439,835, dated November 4, 1890.

Application filed June 19, 1890. Serial No. 357,001. (No model.)

To all whom it may concern:

Be it known that we, JAMES G. CALHOUN, of Edinburg, Portage county, Ohio, and CALVIN B. GARRISON, of Charlestown, in the same 5 county and State, citizens of the United States, have invented a new and useful Improvement in Wire-Twisting Tools, of which the following is a specification.

The main object of our invention is a convenient tool for twisting the sustaining-wires between the consecutive pickets of a fence.

In the drawings forming a part hereof, Figure 1 is a side view of the tool, and Fig. 2 is an edge view of the same.

15 The circular plate *a* is formed with slots *c* for the reception of the wires to be twisted, and is also formed or provided with guides *n* to support and guide sliding handles *b b'*, by which the tool is operated. For convenience 20 the handles are arranged substantially at right angles to each other and on opposite sides of the plate *a*, each handle sliding in and being sustained by two guides *n*. The raised central part *a'* of the plate *a* on each 25 side of the plate strengthens the latter near and between the inner ends of the slots *c*. The handles *b b'* are formed with knobs *s* at their ends to prevent them from sliding out of the plate. The periphery of the plate *a* is 30 formed with depressions *c'* of sufficient depth to receive the knobs *s* to prevent the latter from contact with any fence-brace or other obstruction that may be close to the periphery of the plate *a* while the tool is twisting 35 the fence-wires, sections *o o* of which are shown in one of the slots *c* of Fig. 1.

In operating the tool it is moved forward till the wires *o o* have entered a slot *c*, and is then turned by its handles until the handle *b'* is caused to slide downward by its weight 40 till its end enters the depression *c'*, when the opposite end of the handle may be grasped and the turning thus continued, each handle in turn sliding downward until the twisting is completed. In this manner pressure is con- 45 stantly kept on the wires by means of either one or both of the handles, thus preventing the wires from slipping out of the slot *c* till the work is done. The parts *a'* of the plate *a* are preferably grooved to receive the inner 50 part of the handles. The slots *c* vary somewhat in width to receive different-sized wires, and, if desired, they may be slightly curved outwardly in the direction of motion to hinder the wires from slipping out of the slots 55 during the process of twisting the wires, and also be made flaring at the periphery of the plate *a* to facilitate the entrance of the wires. The guides *n* may be either riveted on the plate, as shown, or cast with and as a part of it. 60

We claim as our invention—

In a wire-twisting tool, a plate formed with slots of varied sizes to receive the wires, in combination with sliding handles on opposite sides of the plate, substantially as described. 65

JAMES G. CALHOUN.
CALVIN B. GARRISON.
